UNITED STATES PATENT OFFICE.

EDWARD W. FURRELL, OF ST. LOUIS, MISSOURI, ASSIGNOR OF ONE-HALF
TO PAUL BAKEWELL, OF SAME PLACE.

RAILWAY-CAR.

SPECIFICATION forming part of Letters Patent No. 340,206, dated April 20, 1886.

Application filed February 11, 1886. Serial No. 191,557. (No model.)

To all whom it may concern:

Be it known that I, EDWARD W. FURRELL, a subject of the Queen of Great Britain, now residing in the city of St. Louis, State of Missouri, have invented certain new and useful Improvements in Railroad-Cars, of which the following is a full, clear, and exact description.

My invention has for its object to prevent the telescoping of railroad-cars and the mounting of one on the other in case of collision; also to increase their strength and rigidity, so as to render them less liable to collapse and be broken up in case of leaving the track or other accident than cars of the ordinary construction.

It consists in the application to the sub-structure or lower frame-work of a railroad-car of auxiliary or supplementary beams or girders of iron or steel plate arranged longitudinally from end to end of the car and provided beyond the said ends with continuations or projecting portions forming spigots and faucets alternately, so that when the cars are coupled the spigots of one car face the faucets of the succeeding car, whereby, in the event of the train being in collision or other accident, the spigots will run into the faucets, and the cars be thereby interlocked, the various girders forming, as it were, continuous girders of great strength and rigidity throughout the train.

On the accompanying drawings, Figure 1 is a sectional plan, broken away, of the end portions of the substructures or bottom frame-works of two consecutive railroad-cars fitted with my invention; Fig. 2, a transverse section on line 1 1 in Fig. 1, to an enlarged scale; and Fig. 3, a front view of parts of Fig. 1, to an enlarged scale—like letters of reference denoting like parts in all the figures.

Fig. 1 A A represent the ordinary substructures or lower frame-works, (broken away,) respectively, of two consecutive railroad-cars.

Between the transverse or end sills, B, of each frame-work A, I arrange two or more longitudinal beams or girders, C, of iron or steel plating, parallel to one another and equidistant from the center line of the frame-work A. On the ends of the girders C are vertical angle-irons D, which, with the said ends, butt against iron plates E, laid against the inside

faces of the sills B. On the outside faces of the latter are similar plates, F, against which, directly in line with or opposite to the ends of the girders C, are placed, respectively, at each end of the car a projection, G, constituting a spigot, and projection G', constituting a faucet or socket. Bolts H, passing through the angle-iron ends D of the girders C, plates E F, sills B, and angle-iron ends I of the projections G G', firmly secure the various parts together. The spigots G, when the cars are coupled, are normally within the mouths of the faucets or sockets G', which are bell-mouthed or flared at their outer open ends, as shown in the front view thereof, Fig. 3, to allow sufficient play around the ends of the spigots G for the oscillation and movements of the cars under ordinary running, the space between the ends of the spigots G and the bottoms of the faucets G' being equal to that between the front edges of the platforms J, which are indicated by dotted lines in Fig. 1.

The girders C may be tubular or rectangular, circular, oval, or any other section, and either flanged and riveted up, as shown in Fig. 2, or built up with angle-irons; or they may be made of double T or any other section, as found most suitable in practice. The girders C may be stiffened vertically by trussing in a similar manner to the longitudinal sills of the framing A, and braced together horizontally by the cross-stays L or otherwise.

If desired, in order to adapt the invention to the existing rolling-stock, the girders C may be divided into sections, according to the number of the transverse beams of the frame-work, and united at their ends; or they may be arranged beneath the frame-work A, in lieu of in the same plane therewith, as shown, in which case the projections G G' will either be formed by the ends of the girders or bolted directly to them.

The spigot projections G may be made of plate iron or steel in a tubular form, similar to the girders C, and their interiors filled with hard wood or other suitable packing, M, to which the plates toward the ends of the spigot are secured by countersunk screws, and elsewhere by riveted stays N, as shown in Fig. 2.

The faucets G' are made of plate iron or

steel in a tubular form, built up externally with angle-irons O, secured by countersunk rivets, so as to present an unobstructed and smooth interior for the entrance of the spigots G. The bottom ends of the faucets G' against the plates F and sills B are filled with hard wood or other packing, P, and the insides of the faucets G', between the packing P and the ends of the spigots G, when these are in their normal position, are of the same size and taper as the tapered end portions of the spigots G.

The spigot and faucet projections G G' may be braced together horizontally by the cross-stays Q, as shown, or otherwise, as found most suitable. On the train being in collision or other accident, the spigots G will run into the faucets G' and be jammed tightly within the inner recesses of the latter until the ends of the spigots G butt against the packings P and plates F in the direct line of girders C, and the cars being thereby interlocked and forming practically a continuous girder uniformly loaded for the entire length of the train, they will be prevented from rising off the track, and the suddenly-checked momentum of the

train being transmitted by direct compression longitudinally through the girders C, the strength and rigidity of the latter will resist the strain and prevent the cars from telescoping, with the consequent smashing and splintering of the wood-work, which is the main cause of loss of life to the passengers.

By my invention the present scantlings of the wood-work used in the construction of railroad-cars may be considerably lightened, and thus the otherwise extra weight of the girders C compensated.

I claim—

In a railroad-car, the application to the lower frame-work of iron or steel plate girders C, in combination with spigot and faucet projections G G' at the ends of the car, substantially as shown, and for the purpose described.

In testimony whereof I have affixed my signature, in presence of two witnesses, this 8th day of February, 1886.

EDWARD W. FURRELL.
